Patented Aug. 27, 1901.

J. JONES.

COMBINED CAR REPLACER AND WHEEL SHOE.

(Application filed Apr. 20, 1901.)

(No Model.)

FIG. 1

FIG. 2

FIG. 4

J. C. Jones.

S. E. Zimmerman.

UNITED STATES PATENT OFFICE.

JAKE JONES, OF WASHINGTON, INDIANA.

COMBINED CAR-REPLACER AND WHEEL-SHOE.

SPECIFICATION forming part of Letters Patent No. 681,228, dated August 27, 1901.

Application filed April 20, 1901. Serial No. 56,679. (No model.)

To all whom it may concern:

Be it known that I, JAKE JONES, a citizen of the United States, residing at Washington, in the county of Daviess and State of Indiana, 55 have invented certain new and useful Improvements in a Combined Car-Replacer and Wheel-Shoe; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to railroad appliances, and has for its object the production of a combined car-replacer and wheel-shoe by which derailed cars may be readily reailed with the minimum loss of time and expenditure of labor 60 20 and by which also broken or otherwise-disabled wheels may be speedily equipped with shoes or runners, thereby permitting movement of the car on the rails without liability of further injury or accident.

25 The nature of my invention will be readily comprehended, reference being had to the following detailed description and to the accompanying drawings, in which—

Figure 1 is a perspective view of a combined replacer and shoe embodying my invention. Fig. 2 is a longitudinal sectional view of the same. Fig. 3 is a cross-sectional view on line 3 3 of Fig. 2. Fig. 4 is a view showing the appliance in use as a car-replacer. 75 35 Fig. 5 is a view showing the appliance in use as a wheel shoe or runner.

Referring to the drawings by letter, A denotes the combined replacer and shoe, which consists of a body portion a , longitudinally curved to conform to the curvature of a locomotive or car wheel periphery. At each end of the body is a hole a' . The outer convex surface of the body is smooth, and the inner concave side is provided with transverse ribs 80 40

45 a^2 a^3 . Extending from the outer surface is a vertical flange a^3 . From the inner surface extends two flanges, one of which, a^4 , projects slightly above the line of the ribs a^2 and the other of which, a^5 , is at the opposite 85 50 side of the body and projects above the line of the flange a^4 . These flanges a^4 a^5 are pro-

vided centrally with sharpened projections or spikes a^6 . Adjacent to the flange a^5 is a depression or channel a^7 , extending the length of the body.

When the appliance is to be employed to replace derailed cars, it is positioned, as shown in Fig. 4, with the flange a^3 uppermost. The device is driven to cause the spikes to enter the tie to hold it firmly, and the difference in height of the flanges a^4 a^5 gives the outer convex surface a transverse slope toward the rail. A device is positioned against each rail and in practice the car-wheels ride on the double inclined surfaces of the devices and are directed to the rails and brought into engagement therewith. 65

In the case of a broken wheel or a sprung axle, which prevents the wheels from revolving without running off the rail, two devices 70 are employed as shoes or runners for the disabled wheels. The devices are inverted to bring the convex side lowermost, and the wheels or truck being jacked up or otherwise raised the devices are positioned to bring the 75 wheel-flanges into engagement with the depressions or channels a^7 and the wheel-tread into engagement with the ribs a^2 . The flanges a^4 and a^5 flank the wheel, and the ribs co-operate to prevent disconnection. Chains b lead 80 from the holes a' to the truck or to the car-body to secure the devices to the wheels. With the devices applied the wheels are prevented from revolving, the devices which rest on the rails acting as runners. The flanges 85 a^3 engage the side of the rail and keep the devices, and consequently the wheels, on the rails.

The combined replacer and shoe being in a single piece may be inexpensively made and 90 is durable.

In use the device is very efficient and reliable and may be applied without the exercise of special skill.

I claim as my invention—

1. A combined car-replacer and wheel-shoe consisting of a body having a flanged convex side, and a flanged concave side provided with ribs engaging the wheel-tread and with a groove for the wheel-flange. 95

2. A combined car-replacer and wheel-shoe consisting of a body one side of which is con-

vex and is provided with a longitudinal flange, and the other side of which is concave and is provided with longitudinal flanges of different heights.

5 3. A car-wheel shoe having an outer tread-surface flanged to engage the rail, and having an inner surface conforming to the wheel tread and flange, flanges at the inner surface to flank the wheel, and chains connecting the

shoe at opposite ends with the truck or car-body.

In testimony whereof I affix my signature in presence of two witnesses.

JAKE X JONES.
